UNITED STATES PATENT OFFICE.

PAUL R. H. LENZ, OF LOS ANGELES, CALIFORNIA.

OIL-BURNER.

1,268,587.

Specification of Letters Patent. Patented June 4, 1918.

Application filed January 16, 1918. Serial No. 212,087.

To all whom it may concern:

Be it known that I, PAUL R. H. LENZ, a citizen of the United States, residing at Los Angeles, in the county of Los Angeles and State of California, have invented a new and useful Oil-Burner, of which the following is a specification.

- My invention relates to burners for burning petroleum and similar hydrocarbon oils.
- 10 One object of the invention is to thoroughly mix and burn the oils smokelessly.
- Another object is to provide a primary burner for smokelessly heating the retort before the fuel is heated by the whole burner.
- 15 Another object is to construct the main burners so that they can be placed with their orifices away from or toward the retort so as to change the heating capacity of the burners in relation to the retort.
- 20 Another object is to provide suitable air mixing and heating chambers through which the vaporized fuel has to pass.

- Another object is to provide vaporizing means within the retort.
- 25 Another object is to provide a second primary heating means for the fuel to be heated before the burner is in operation.

Other objects will appear from the following description and appended claims as well as from the accompanying drawing, in which—

Figure 1 is a side elevation of my complete burner.

Fig. 2 is a cross section on line 2—2 of Fig. 1.

Fig. 3 is a fragmentary cross section of the burners showing the orifices of the burners slightly inclined toward the middle to illustrate that the burner tubes are turnably mounted to allow such movement.

Fig. 4 is another fragmentary cross section with the burner tubes turned to bring the orifices farther apart.

Similar numbers refer to similar parts throughout the several views.

In Fig. 1, 5 designates the supply pipe which forms the retort for my burner having the downwardly extending arm 6, terminating in the two discharging ends 7 and 8. The supply pipe 5 is secured to the mixing chamber 11 by the plate 9 and the bolt 10. The mixing chamber is provided with an extension end 12 into the open end of which the discharging end 7 leads, as indicated at 13. A boss 14 is provided on the outside of the mixing chamber, being threaded for

the valve stem 15. The valve stem 15 is provided with a needle valve 16 engaging with the discharging end 7 of the supply pipe. The hand wheel 17 is for adjusting the valve 60 in relation to the opening in the discharge end 7 by screwing the stem 15 farther into and through the boss 14 thereby shutting off the opening in the discharge end 7 more or less, or by turning back the stem 15 so as 65 to withdraw the needle valve from engagement with the boss or discharge end 7. A suitably formed bearing 18 is provided within the extension end 12 of the mixing chamber, see also Fig. 2, for guiding the needle valve into the opening of the discharge end 7.

A mixing chamber 19 with an extension end 20 similar to the mixing chamber 11 and the extension end 12 inclose the needle valve and stem designated at 21 and 22, arranged oppositely the discharge end 8 of the supply pipe.

A suitable number of recesses provided in the walls of the mixing chambers 11 and 19 80 as indicated at 23 serve to receive and support the burner tubes 24 and 25. The mixing chambers are provided with openings 26 allowing a communication of the mixing chambers with the inside of the burner 85 tubes. The burner tubes are open at the end adjacent to the mixing chambers having suitable flanges 27 fitting and resting in the recesses 23 held in such position by the plates 28 which are secured to the mixing chambers by the bolts 29. The free ends 30 of the burner tubes are closed causing the gas mixture to pass out of the narrow slots 31, forming the orifices for and of the burner.

Mounting the burner tubes turnably on the flanges 27 makes it possible to turn and set the orifices in the tubes at different angles in relation to the retort as can be more clearly seen and understood from the 100 Figs. 2, 3 and 4. The gas escaping out of the orifices in the burner tubes when set as illustrated in Fig. 2, only strikes and passes partly around the burner supply pipe 5, as indicated at 32; while the gas passes almost 105 with its full force around the supply pipe 5 when the burner tubes are turned and set to bring the orifices to the position illustrated in Fig. 3, as indicated at 33, producing and causing a much better heating of the 110 fuel passing through the supply pipe before such fuel passes into the mixing chamber, as

will easily be understood; and on the other hand, when turning the burner tubes to bring the orifices farther apart or to a position as illustrated in Fig. 4, the gas naturally passes much less around the supply pipe 5, the burning gas giving very little heat to the passing fuel in the supply pipe 5.

With this arrangement it is possible to 10 heat the fuel passing through the supply pipe corresponding to the fuel used in a certain furnace to procure the right mixture and correctly heated mixture for different kinds and sizes of furnaces without having 15 to construct different sizes for slightly different furnaces. This arrangement allows also to use different kinds of fuel in the same burned by simply setting the burner tubes correspondingly to heat the fuel properly 20 in relation to its gravity, as will easily be understood.

To intensify, increase, or force the vaporizing of the fuel in this burner, a wire coiled properly is placed into the supply 25 pipe 5 having the coils gradually increasing from the ends 34 toward the middle 35.

In case that no suitable fuel oil is on hand, an electrically operated heater is provided on the burner, consisting in the plates 30 36 and 37, which are soldered or welded together around the edges so as to form a suitable space between the plates, and suitable coils 38 disposed in a suitable casing 39 adjacent to the plates 36 and 37 are connected to an electric current at 40. Sending a suitable electric current through the coils 38 naturally throws the heat from the coils toward the plates 36 and 37, thereby 35 heating the fuel passing through the small space between the plates. At one place, of course, the plates are not welded together, where a suitable connection 41 is secured 40 for directing the fuel supply through the space between the plates, as will easily be 45 understood.

For heating the fuel, passing through the supply-pipe 5, when starting the burner, an oil pan 42 is provided on the mixing chamber at a suitable place below the supply 50 pipe. A wick 43 is placed into the pan 42 held between the carriers 44 with the upper edge a suitable distance below the supply-pipe 5 and between the burner tubes 24 and 25 so as to heat the fuel passing through 55 the supply pipe before it enters the burner tubes and so that the gas procured from the fuel and the air passing through the mixing chamber out of the burner-tubes may be ignited by the flame of the primary burner 60 formed by the wick 43, the pan 42 and the carriers 44. The carriers 44 are provided with suitable perforations 45 to allow air to pass near the wick 43 at its upper edge, through the space formed between the wick 65 and the carriers.

Starting this burner, by either heating the fuel when passing through the electric heater arranged in the supply line or by using the primary burner below the supply-pipe as described, the heated and partly vaporized fuel is directed through the discharging end 7 into the mixing chamber at 13, there mixing with the air passing into the mixing chamber at the same point, the gas mixture passing through the chamber 12 and upwardly through the chamber 11, escaping through the openings 26 into the burner tubes 24, hence out of the orifices 31 in the burner tubes where the gas is ignited. Having developed enough gas to 75 burn a suitably large flame from the orifices of the burner tubes, the primary burner is not necessary any longer, as the flame on the burner tubes can be regulated as described above in relation to Figs. 2, 3 and 4, by turning the burner tubes to cause the flame to directly strike the supply pipe 5 as illustrated in Fig. 3, or by turning the burner tubes so that the full force of the flame from the burner tubes escapes practically 80 vertical, striking the supply pipe 5 only partly as illustrated in Fig. 2, or by turning and setting the burner tubes as illustrated in Fig. 4 so that the flame from the burner tubes is not really passing directly 85 around the supply pipe 5. The arrangement illustrated in Fig. 3 is naturally suitable for developing enough gas to burn the burner with full force by opening the needle valve 16 correspondingly. This arrangement is also suitable for rather heavy fuel or fuel which requires a rather strong primary heating before it escapes out of the burner, while fuel which requires less heating while passing through the supply pipes 90 allows a turning and setting of the burner tubes as illustrated in Figs. 2 and 4. From this it will easily be understood that the primary heating by an electric heating system or by the primary burner between the 95 burner tubes is only used for a very short time while the heat from the flame of the burner tubes is normally heating the fuel passing through the supply pipe as described. 100

So far the burner is described in its operation to one half of the device illustrated in Fig. 1, which is enough for and under normal conditions, but for extra strong burning and for developing extra strong heat, the second part of the device illustrated in Fig. 1 is provided to allow a forcing of suitable heat in furnaces where such forcing is required. In such a case, the needle valve 21 is opened allowing gas to enter the chamber 20 to pass farther upwardly through the chamber 19, into the burner tubes 25. The burner tubes can easily be set so as to cause the flame from the burner tubes 24 to pass around the supply pipe 5 to a suitable part 110 115 120 125 130

as to develop enough gas for the burner tubes 24 as well as for the burner tubes 25, as will easily be understood.

Having thus described my invention, I 5 claim:

1. In a burner of the class described two burner tubes arranged in practically horizontal and parallel position having a suitable number of orifices, a mixing chamber 10 arranged below the burner tubes in its horizontal part having also a practically vertical part, the horizontal part terminating in an open end while the vertical part has communicating openings for the burner tubes, the vertical part is also provided with circular recesses near the communicating openings, the burner tubes being closed on one end while the other end is provided with a flange turnably fitting in the circular recesses of the mixing chamber, and suitable means provided for movably holding the burner tubes engaged within the recesses of the mixing chambers with the orifices in the burner tubes in the desired position. 25
2. In a burner of the class described a mixing chamber, burner tubes having communication with the mixing chamber, a fuel supply pipe disposed above the burner tubes, and a primary burner provided on the mixing chamber between two of the burner tubes and below the supply pipe, the primary burner comprising a pan provided on the mixing chamber, a wick disposed in the pan, and a wick carrier having 30
3. In a burner of the class described in combination with a mixing chamber, burner tubes having communication with the mixing chamber, a fuel supply pipe disposed above the burner tubes, and a primary burner provided on the mixing chamber below the supply pipe; an electrically operated heating and vaporizing means disposed in the supply line at a suitable place before the supply pipe passes over the burner tubes. 35
4. In a burner of the class described in combination with a mixing chamber having burner tubes in a practically horizontal position and a fuel supply pipe disposed above the burner tubes terminating at a suitable place within the mixing chamber; an electrically operated heating and vaporizing means comprising two plates adjacent to each other 40 having the edges joined air-tight up to a suitable distance for fuel inlet connection and another suitable distance for connection of the said fuel supply pipe, and a suitable coil disposed adjacent to the plates having 45 connections for an electric current. 50

In testimony whereof I hereunto affix my signature in the presence of two witnesses.

PAUL R. H. LENZ.
